(57) CLAIM

The ornamental design for a paper roll holder, as shown and described.

DESCRIPTION

FIG. 1 is a perspective view of a paper roll holder showing my new design;

FIG. 2 is a perspective view of a paper roll holder showing my new design in use;

FIG. 3 is a left side elevation view thereof;

FIG. 4 is a right side elevation view thereof;

FIG. 5 is a right back elevation view thereof;

FIG. 6 is a left back elevation view thereof;

FIG. 7 is a top plan view thereof;

FIG. 8 is a bottom view thereof; and,

FIG. 9 is a section view thereof in use.

The broken lines depict environmental subject matter only and form no part of the claimed design.
